UNITED STATES PATENT OFFICE.

CLINTON M. COTTERMAN, OF PYRMONT, OHIO.

GRAVEL-BED FOR WAGONS.

SPECIFICATION forming part of Letters Patent No. 361,675, dated April 26, 1887.

Application filed January 26, 1887. Serial No. 225,537. (No model.)

To all whom it may concern:

Be it known that I, CLINTON M. COTTERMAN, of Pyrmont, in the county of Montgomery and State of Ohio, have invented a new and Improved Gravel-Bed for Wagons, of which the following is a specification.

Hitherto in the usual wagons or carts intended for carrying sand, gravel, &c., the bed of the wagon has been composed of a series of slats running lengthwise of the wagon, which are removed one by one in order to dump the contents of the wagon. To facilitate the dumping and obviate the necessity of removing the slats separately, the slats have been eccentrically pivoted at their ends and provided with operating mechanism, so that they can all be turned or caused to turn simultaneously.

The present invention relates to gravel-beds of this character; and it consists in the arrangement of the slats and in the mechanism for operating the same.

The invention is illustrated in the accompanying drawings, in which—

Figure 1 is a side view, Fig. 2 a longitudinal section, and Fig. 3 a cross-section, of a wagon-body provided with the present improvements.

A is the body of the wagon, and B B the slats eccentrically pivoted to the ends thereof. The slats, owing to their eccentric pivots, normally hang downward, as shown in Fig. 3, leaving a space between them for the discharge of the sand, gravel, &c. The central slats are pivoted so as to swing toward each other, and the side slats swing, respectively, in the same way—that is, all swing toward the center away from the sides of the wagon. This is important, since as the slats never reach a vertical position, but in their lowest position incline toward each other, the sand or gravel from both sides is directed toward the center, and is thus deposited more compactly than otherwise would be the case.

Beneath the slats are two or more crank-shafts, C C, their cranks $\alpha\alpha$ having their bearings in the sides of the wagon. Connected to one of the cranks α (preferably the forward one) is an upwardly-extending operating-handle, D, which is connected to a vertical

arm, b, on each of the other cranks by a horizontal rod, E. By this means all of the crank-shafts are moved simultaneously and equally. A guard, c, holds the handle in place and limits its movement in both directions.

When the handle D is in the position shown in Fig. 1, the crank-shafts are in their highest positions, and when the handle is moved in the direction of arrow 1 the shafts are lowered.

When the shafts are in their highest position, the upper surfaces of the slats are horizontal and flush with each other, and the weight of the gravel, &c., is supported by the shafts. When the shafts are lowered, the weight of the gravel causes the slats to turn on their pivots, and the gravel is discharged through the spaces between them. When the shafts have reached their lowest position, the edges of the slats rest upon them, the slats being inclined, as shown in Fig. 3, so that when the edges are again turned upward the slats are swung into position.

I claim as my invention—

1. The bed composed of slats eccentrically pivoted, in combination with cranked shafts beneath the same, on which the slats rest, substantially as set forth.

2. The bed composed of slats eccentrically pivoted, the slats on opposite sides being pivoted so as to turn toward the center and toward each other, in combination with cranked shafts beneath the same, on which the slats rest, substantially as set forth.

3. The wagon-body A and slats B B, eccentrically pivoted to the ends thereof, in combination with the shafts C C, having cranks $\alpha\alpha$ mounted in bearings on the sides of the wagon-body, the operating-handle D, connected to one of said cranks, vertical arms b, connected to the other cranks, and rod E, connecting the handle D and the arms b, substantially as set forth.

In witness whereof I have hereunto signed my name in the presence of two subscribing witnesses.

CLINTON M. COTTERMAN.
